COUNTERSINK

Clarence M. Eveleth, River Forest, Ill.

Application October 16, 1939, Serial No. 299,747

4 Claims. (Cl. 145—123)

This invention relates to a tool comprising a stop and a countersink member journaled in the stop, the stop limiting the amount that the countersinking member enters the material. The present invention aims to provide novel means whereby the stop will be prevented from marring finely finished surfaces.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawing:

Fig. 1 shows in elevation, a device constructed in accordance with the invention, parts being broken away;

Fig. 2 is a bottom plan;

Figs. 3, 4 and 5 are diagrammatic elevations illustrating the operating of the device which characterizes this application.

The numeral 1 marks a tubular casing provided at its lower end with a foot 2 whereon a sleeve 3 is secured by threading, the sleeve being provided at its lower end with an inwardly extended, annular flange 4. The numeral 5 designates a tubular stop, having a head 6 received between the flange 4 of the sleeve 3 and the foot 2 of the casing 1, the construction being such that there can be relative movement between the casing and the stop, so far as rotation is concerned.

The numeral 7 marks a countersink bit extended through the casing 1 and the stop 5, the bit having a working end 8. The countersink bit 7 is threaded at 9 into the casing 1, for adjustment, to determine the amount that the working end 8 of the bit projects downwardly beyond the lower end of the stop 5, and to determine the depth of the countersink. After the countersink bit 7 has been adjusted longitudinally with respect to the casing 1, the countersink bit is held in its adjusted position, by means of a jamb nut 10 engaged with the threads 9 of the countersink bit and engaging the upper end of the casing 1. The part 11 is a knurled collar formed on the casing 1, whereby the cas-

ing can be held against rotation whilst the jamb nut 10 is being tightened up.

After the desired longitudinal adjustment of the countersink bit 7 has been attained, and the jamb nut 10 set against the end of the casing 1, the casing 1 and the bit 7 turn as one piece. Grossly considered, the device as thus far described comprises a countersink tool, including both the casing 1 and the bit 7, and a tubular stop, to wit, the part 5, the stop and the countersink tool being connected together for relative rotation.

Generally stated, the countersink tool, including the bit 7 and the casing 1, is rotated and the working end 8 of the bit forms a countersink in the material. The depth of the countersink is determined when the lower end of the stop 5 comes into contact with the material. Such a combination of parts, and the resulting operation, are reasonably satisfactory if rough material is being countersunk. If, however, a finely finished or polished material is being countersunk, it will be damaged or marred by contact with the lower end of the stop 5. This invention aims to provide a simple but effective means whereby such a contingency will be avoided.

The stop 5 is provided at its lower end with circumferentially spaced fingers 12. In the lower end of each finger 12, and at one side thereof, a rectangular recess 14 is formed. A bore 15 in the finger 12 leads upwardly from the lower end of the finger, past the recess. A cushion 16 is secured in the bore 15, and, preferably, is a cylindrical rubber plug. The plug 16 is long enough so that in its normal condition, it projects downwardly below the lower end of the finger 12, as Fig. 3 will show. The upper wall of the recess 14 is rounded, as shown at 17. This is done to the end that when the lower end of the plug 16 is flexed laterally, as in Figs. 4 and 5, the plug 16 will not be cut. In the upper wall of the recess 14, a circumferentially extended groove 18 is formed, the groove being shaped to correspond with the cross section of the plug 16.

In practical operation, the countersinking tool 7—1 is rotated, and the working end 8 of the countersink bit 7 forms a countersink in the material. When the finger 12 is rotated in the direction of the arrow A in Fig. 3, the lower end of the plug 16 comes into contact with the material. The problem presented at this stage is to stop the rotation of the member 5, under the drag of the countersinking tool. That is done by pressing the tool down, as shown by the arrow B in Fig. 4, until the lower end of the plug 16 is 55

brought into close frictional contact with the work. The lower end of the plug 16 retires into the recess 14, and is held against lateral swinging movement, because the lower part of the 5 plug is received in the groove 18.

The rotation of the stop 5 now has been terminated, the parts being in the position of Fig. 4, but that is not enough. The tool must be pressed downwardly, in the direction of the arrow C in Fig. 5, until the lower end of the finger 12 comes into contact with the work. That contact determines positively, the depth of the countersink formed by the working end 8 of the bit 7. If the lower end of the finger 12 were not 15 brought into contact with the work, the depth of the countersink could not be determined definitely, because the plug 16 is compressible.

The recess 14 exercises two functions. It provides a space into which the flexed lower 20 end of the plug 16 can retire, as in Fig. 4. Moreover, since the lower end of the plug 16 does not have to be compressed throughout its entire cross section, it is not difficult to bring the finger 12 down from the position of Fig. 4, to a definite 25 stop on the material, as depicted in Fig. 5.

The device is simple, but considering that it is to be used on polished or finely finished work, problems are presented which are more complex than a casual inspection of the drawing might 30 lead one at first to suppose; and minutiae in structure are not without useful function and patentable consequence.

Having thus described the invention, what is 35 claimed is:

1. In a device of the class described, a rigid material-engaging stop having a bore at its lower end, a countersink tool journaled in the stop, and a compressible, material-engaging cushion carried by the bore in said stop and projecting

below the lower end of the stop, the stop being provided at its lower end with a recess leading into said bore and into which the cushion can retire when flexed laterally, the depth of the recess being less than the diameter of the cushion.

2. In a device of the class described, a rigid material-engaging stop having a bore at its lower end, a countersink tool journaled in the stop, and a compressible, material-engaging cushion carried by the bore in said stop and projecting below the lower end of the stop, the stop being provided at its lower end with a recess leading into said bore and into which the cushion can retire when flexed laterally, the depth of the recess being less than the diameter of the cushion, and the stop being provided, at the upper wall of the recess, with a circumferentially extended groove, receiving a portion of the cushion.

3. In a device of the class described, a rigid material-engaging stop having a longitudinal bore and a lateral recess in its lower end, the recess leading to the bore, a compressible, material-engaging cushion mounted in the bore and projecting beyond the lower end of the stop, the height of the recess being less than the diameter of the cushion, the cushion being laterally flexible to enter the recess, the stop being rounded at the place of juncture between the recess and the bore, to prevent the cushion from being cut when flexed, and a countersink tool journaled in the stop and extended downwardly below the stop.

4. A device of the class described, constructed as set forth in claim 3 and wherein the stop has a circumferentially extended groove, located in the upper wall of the recess, and shaped to receive the flexed cushion.

CLARENCE M. EVELETH.
